(57) **CLAIM**

The ornamental design for a dual-leg ledge shelf as shown and described.

DESCRIPTION

FIG. 1 is a top, front, right side perspective view of a first embodiment of a dual-leg ledge shelf showing our new design;

FIG. 2 is a bottom, back, left side perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a top, front, right side perspective view thereof shown with an environmental window ledge;

FIG. 10 is a top, front, right side perspective view of a second embodiment of a dual-leg ledge shelf showing our new design, the only difference being the supporting leg portion includes a two-piece alternate configuration;

FIG. 11 is a bottom, back, left side perspective view thereof;

FIG. 12 is a front elevation view thereof;

FIG. 13 is a rear elevation view thereof;

FIG. 14 is a left elevation view thereof;

FIG. 15 is a right elevation view thereof;

FIG. 16 is a top plan view thereof;

FIG. 17 is a bottom plan view thereof; and,

FIG. 18 is a top, front, right side perspective view thereof shown with an environmental window ledge.

Dash-dot broken lines indicate a break in the width, and the appearance of any portion of the article between each of the sets of dash-dot broken lines, and the dash-dot broken lines themselves form no part of the claimed design.

Evenly-spaced dashed lines are included to show environmental elements and/or supplemental structure(s) in the drawings that form no part of the claimed design.

(Continued)

Dash-dot-dot lines indicate enclosed boundary areas which form no part of the claimed design, and the dash-dot-dot lines themselves form no part of the claimed design.

1 Claim, 16 Drawing Sheets
